ENGINE SCAVENGING SYSTEM

Rudolph Schneider, St. Louis, Mo., assignor to
 Busch-Sulzer Bros.,-Diesel Engine Company,
 St. Louis, Mo., a corporation of Missouri

Application November 12, 1930, Serial No. 495,072

2 Claims. (Cl. 123—65)

The invention relates to multi-cylinder combustion engines, more especially two-cycle injection engines, the object being simplification of the engine and particularly its air supply system, 5 greater compactness, and improvement in its general structural and operating efficiency as hereinbelow made apparent to those skilled in this subject.

The drawings hereto represent a preferred 10 form of the invention, Fig. 1 being a transverse vertical section on line I—I of Fig. 2. Fig. 2 a top plan with parts broken out and Fig. 3 a side elevation, also with parts broken out.

The engine taken for illustration comprises six 15 engine cylinders arranged in a straight row as customary, and each comprising a cylinder proper marked 2, and a liner 3 associated therewith to form the usual water jacket space between them. The cylinder head 4, though not so shown, will 20 be understood to be supplied with the usual valve mechanism appropriate to the type of engine on which the invention is employed. Each liner 3 is formed with a semi-circular set of exhaust port slots 5 opening to the exhaust manifold 6 also as customary in 2-cycle engines, and with a 25 similar set of air port slots 1, both sets being uncovered or opened by the piston toward the end of its working stroke. Reverse flow through the air ports is prevented by check valve mechanism 30 which is shown according to the design of patent September 30, 1924, No. 1,510,143, in which a vertical series of pivoted plates or louvres 8, contained in a suitable box or frame, swing inwardly automatically under the effect of air flow to 35 the cylinder, but close by their gravity against reverse flow. While other types of valve might be employed, with equal function, it is desirable and preferred to use one in which the passage is closed by a multiplicity of small plates or 40 louvres which can be arranged vertically one above the other, thus obtaining adequate flow capacity with the least extent of lateral projection from the cylinder wall, and thereby accommodating and promoting the object of this new 45 combination as will presently appear.

Air is supplied through these inlet valves to the cylinders directly from the interior of a long horizontal blower casing marked 9—10, which 50 according to this invention takes the place and position of the familiar horizontal air receiver or air manifold commonly employed in two-cycle engines. Such air manifolds, as well known, are large of diameter in order to minimize air flow resistance and heretofore they have been supplied with air through a connection with a single

rotary blower usually situated at one end of the row of cylinders and being of large dimensions in order to supply all the cylinders and therefore occupying considerable space. The blower of this invention takes the place of such common air receiver and, as may be observed in the drawings, requires but little more space on the engine than was formerly occupied by the air receiver alone. The body part 9 of the blower casing is bolted directly to the engine cylinder 10 structure, and the other part 10 is bolted to the first, the bolts being omitted from the drawings for convenience of illustration. The casing may be built up of more than two parts if desired and may have such internal configuration as is required for the type of air impeller or rotor that is used. It extends the full length of the row of cylinders it serves and is secured to them in a position well above the crankcase enclosure as indicated in Fig. 1, so that the latter and the 20 parts therein are readily accessible beneath it. Its interior space is open laterally to all of the air inlet valves 8, which are in fact located within the casing and covered by it.

The important characteristic of the impeller 25 system within this casing is that it is extended or elongated in the direction of the rotary axis and like its casing is practically co-extensive with the row of engine cylinders. With such extended axial dimension, the lateral or radial dimension 30 of the rotor or rotors proper may be relatively small, thus keeping the width of the casing not objectionably larger than the old type air receiver which it displaces. In the case in hand the impeller means is of the Roots blower type with 35 its rotor elements axially elongated as stated but divided in two sections, arranged end to end and together constituting a single blower. The two mating rotors on the left hand side of Fig. 3, marked 12 and 13 respectively, constitute one section of the impeller system and the two rotors at the right hand, marked 14 and 15 are the other; rotors 12 and 14 being co-axial with each other and 13 and 15 being also co-axial; they could be on the same shafts. Each rotor in the present 40 case is mounted on independent bearings of its own at the ends of the casing and at the middle on a dividing wall 16, which appears in Figures 2 and 3, and each rotor couple draws in atmospheric air through inlet 17 and delivers it into 50 the long horizontal chamber 18 which is a common delivery chamber or passage for both couples common also to all of the inlet valves 8 and engine cylinders. This chamber 18 is formed by the space between the impeller system and interior

partitions 11 and the cylinder structure, and its capacity is great enough to give some smoothing out of the pressure pulsations produced by the rotors thus promoting uniformity of pressure in the air delivery to the cylinders. Further uniformity is produced by the relative angular displacement of the rotor couples of the sections, that is to say, by advancing rotor couple 12-13 about 45° on their axes with relation to rotor couple 14-15 thus overlapping their respective pressure curves and producing a steadier head, and a still greater degree of uniformity can obviously be obtained by dividing the impeller system into a greater number of longitudinal sections or couples, no two of which coincide in pressure effect. But two sections angularly displaced as stated and delivering to the common air chamber 18 are found to be adequate for all ordinary purposes.

20 The impeller means can be driven in any appropriate way, for instance rotor couple 12-13 is driven by a spur gear couple 19 and sprocket chain or geared belt 20 from one end of the crankshaft and the other couple is driven by similar spur gear couple 21 and sprocket chain 22 from the opposite end of the crankshaft. By locating the axis of the upper rotors closer to the engine cylinders than the lower rotor the sprocket chains have a more nearly vertical position and the vertical height of the blower casing is correspondingly though slightly shortened.

It will be apparent from the description above given that the principle of the invention comprises the organization of the blower mechanism in a long horizontal housing or casing, directly on the row of engine cylinders in place of the ordinary air receiver, and preferably divided in longitudinal sections of which the rotors are angularly displaced, and deliver to the horizontal air chamber which is common to more than one engine cylinder; and within this principle that the apparatus may take various forms different from that herein shown for illustration of the invention.

45 The following is claimed:

1. The improvement in multi-cylinder, two-cycle, injection type engines which consists in the combination with a row of upright water-jacketed

engine cylinders, each of the fuel injection type, and each having a piston-controlled cylinder port for admitting scavenging air thereto independently of fuel, and a non-return valve governing said port, of a horizontal casing structure longitudinally substantially co-extensive with the length of said row and attached to the cylinder jacket thereof above and below the level of said air ports, said casing containing an air-impeller chamber and a pulsation-absorbing chamber in 10 parallel relation to each other, said pulsation-absorbing chamber extending horizontally and substantially continuously for the full length of said casing between said impeller chamber and the jacket wall of the cylinders, and said impeller chamber housing a plurality of rotors of relatively short radius and elongated axial dimension, said rotors delivering scavenging air through said air chamber to said air valves, and means for driving the rotors at velocities adapted for 20 air-scavenging purposes.

2. The improvement in multi-cylinder two-cycle injection engines which consists in the combination with a row of upright water-jacketed engine cylinders, each of the fuel injection type 25 and each having a piston-controlled cylinder port for admitting scavenging air independently of fuel thereto and a non-return valve governing said port, of a horizontal casing structure longitudinally substantially co-extensive with the 30 length of said row and attached to the cylinder jacket thereof above and below said air ports, said casing containing an air-impeller chamber and a pulsation-absorbing chamber in parallel 35 relation to each other, said pulsation-absorbing chamber extending horizontally and substantially continuously for the full length of said casing between said impeller chamber and the jacket wall of the cylinders, and said impeller chamber housing a plurality of pairs of rotors of relatively short radius and elongated axial dimension, delivering scavenging air through said air chamber to said air valves, said pairs of rotors being in alignment and angularly displaced relatively to each other, and means for driving the 40 rotors at velocities adapted for air scavenging purposes.

RUDOLPH SCHNEIDER.
